UNITED STATES PATENT OFFICE.

HENRY F. PARKER, OF BROOKLYN, NEW YORK, ASSIGNOR TO THE COAST PIGEON MANUFACTURING COMPANY, OF CUYAHOGA FALLS, OHIO.

DESIGN FOR A FLYING TARGET.

SPECIFICATION forming part of Design No. 27,881, dated November 16, 1897.

Application filed February 26, 1897. Serial No. 625,220. Term of patent 14 years.

To all whom it may concern:

Be it known that I, HENRY F. PARKER, a citizen of the United States, residing at the city of Brooklyn, in the county of Kings and State of New York, have invented and produced a new and original Design for Flying Targets, of which the following is a specification, reference being had to the accompanying drawings, forming part thereof.

Figure 1 is a top face view of a target showing the design. Fig. 2 is a cross-section at x , Fig. 1, these two views being deemed necessary to fully illustrate the design.

The design applies to a saucer-shaped target of brittle composition for trap-shooting.

The leading feature of the design consists in a series of embossments closely arranged and undulating in continuous succession in the direction of the circle of the target and without intermission.

The embossments d are closely arranged and radiate in straight lines from the center D to

the annulus B and bear the design of feathers. The embossments b are arranged to form a continuous series of undulations around the 25 target, occupying the space between the annulus B and the rim A . Said embossments b bear the design of feathers and are so arranged as to resemble several series of overlapping feathers, as shown in Fig. 1. The 30 under surface of the target is formed with concave surfaces corresponding in position with the convex surfaces of the upper side of the target, so that the thickness of the material is substantially the same throughout that 35 portion above the rim A .

What I claim is—

The design for a flying target herein shown and described.

HENRY F. PARKER.
